UNITED STATES PATENT OFFICE.

JOHN SOUDER, OF PHILADELPHIA, PENNSYLVANIA.

COMBINATION BILL-HEAD, DUPLICATE, LABEL, RECEIPT, AND ENVELOP.

No. 846,064.

Specification of Letters Patent.

Patented March 5, 1907.

Application filed September 20, 1906. Serial No. 335,452.

To all whom it may concern:

Be it known that I, JOHN SOUDER, a citizen of the United States, residing in the city and county of Philadelphia, State of Pennsylvania, have invented a new and useful Combination Bill-Head, Duplicate, Label, Receipt, and Envelop, of which the following is a specification.

My present invention consists of a novel and useful combination bill-head and duplicate, label, receipt, and envelop, by the employment of which the time and labor employed in making out the different slips is reduced to a minimum.

15 It further consists of a novel construction of a sheet which is scored, perforated, and cut in such a manner that any desired portion thereof may be removed and the remainder folded, closed, and sealed.

20 It further consists of a novel construction of a combination bill-head and duplicate, label, receipt, and envelop having any desired printing thereon and scored, cut, and perforated in such a manner that after the 25 carbon has been placed in position between the different sheets all of the writing may be accomplished at a single operation without turning or refolding the device.

It further consists of other novel features 30 of construction, all as will be hereinafter fully set forth.

In order to illustrate my invention, I have shown those embodiments thereof which at present are preferred by me, although it is to be understood that various changes in the 35 form, arrangement, and location of the different elements may be made without departing from the spirit and scope of the invention.

40 Figure 1 represents a perspective view of a combination bill-head and duplicate, label, receipt, and envelop embodying my invention. Fig. 2 represents a perspective view thereof, showing one portion thereof as folded 45 and having a sheet of carbon inserted in position. Fig. 3 represents a perspective view thereof, showing the next stage of operation.

Fig. 4 represents a perspective view showing the position the parts assume at a further 50 stage of the operation. Fig. 5 represents a section on line $x-x$, Fig. 4. Fig. 6 represents a section on line $y-y$, Fig. 4. Fig. 7 represents a perspective view showing the position the parts assume before the same are folded 55 ready for delivery and after the duplicate and label have been removed. Fig. 8 represents

a perspective view showing the position the parts assume during the folding operation. Fig. 9 represents a perspective view showing the device ready for delivery. Fig. 10 represents a perspective view of another embodiment of my invention, showing the device as provided with flaps and the top flap of the envelop as being provided with suitable adhesive material. Fig. 11 represents a perspective view of the embodiment seen in Fig. 10, showing the same as sealed and ready for delivery.

Similar numerals of reference indicate corresponding parts in the figures.

Referring to the drawings, 1 designates a combination bill-head and duplicate, label, receipt, and envelop embodying my invention, the same being formed of a single sheet of paper or other suitable material which is 75 suitably scored, as indicated at 2, 3, and 4, perforated, as indicated at 5, 6, 7, 8, and 9, and cut, as indicated at 10.

It will now be apparent from Fig. 1 that owing to the manner in which the device is 80 cut, perforated, and scored that the sheet is divided into a label 11, receipt-slip 12, a duplicate slip 13, a bill-head 14, sides 15 and 16 of the envelop portion, and the flap 17. This flap 17 is provided with a tab 18, which when the 85 parts are in assembled position engages the slit or groove 19 in the envelop side portion 15. The side 16 is paneled or cut out, as indicated at 20, in order that the upper portion 21 of the bill-head 14 will be in such alignment therewith when the parts are folded for delivery that the name and address written on said portion 21 may be clearly seen, as is evident.

It is to be noted that in the present instance I have shown the label 11 and the receipt 12 as being cut away, so that the prices will not appear on either the label 11 or receipt 12, but will be seen only on the bill-head 14 and the duplicate 13, as will be 100 readily apparent from Figs. 3 and 4, although it is to be understood that the cutting away of said label and receipt is not essential in all cases.

The operation will now be readily apparent 105 to those skilled in this art. The envelop is first placed on the reverse face to that seen in Fig. 1, and a sheet of carbon 22 is placed face down on the duplicate slip 13. This duplicate slip 13 is then folded together with 110 the carbon-sheet 22, the parts now appearing as indicated in Fig. 2, it being understood

that the folding of this duplicate slip 13 is permitted, owing to the manner in which the sheet is cut, as indicated at 10, and perforated, as seen at 8. The label 11, the receipt 12, and the duplicate 13, folded thereon, between which the carbon-sheet 22 is placed, are now folded to the right, so that the parts appear as seen in Fig. 3, it being understood that the folding of these parts is permitted, 5 owing to the provision of the perforations 5 and 7. 23 designates a second sheet of carbon which is now placed over the receipt-slip 12 and the label 11. The bill-head 14 is now folded over, so as to engage the carbon-sheet 10 15 23, the parts now appearing as indicated in Fig. 4. The bill-head is now ready to be made out, and all the printing or writing is done on a single side of the sheet. It will be seen that when the address is written, owing 20 to the portion 21 of the bill-head extending over the label 11, that the receipt portion 13 is folded in such a manner that the carbon copy of this address will be made out not only on the label 11, but also on the duplicate slip 13, and that also a carbon copy of the bill will be made on the receipt-slip 12 and also on the duplicate 13. The carbon-sheets 22 and 23 are now removed, and the label 11 and the duplicate 13 are removed. 25 30 The receipt-slip 12 may remain attached to the portion 15, if desired, and this may be folded against said portion 14, the parts now appearing as seen in Fig. 7, although it will be apparent that the receipt 12 may 35 be removed after the same is signed, if so desired. The device is now ready to be folded, it being noted that the bill-head 14 is first folded toward the portions 15 and 16, and the portion 21 of the bill-head 14, on 40 which the address is written, is folded in a reverse direction, and the flap 17 is folded toward the bill-head 14, the parts now appearing in a partly-folded position, as seen in Fig. 8. The addressed portion 21, the bill-head 14, and the envelop portion 15 are 45 now folded so that the addressed portion 21 is in alinement with the panel or cut-away portion 20 of the side 16 and the flap 17 is deflected over the portion 15 and the tab 18 is 50 inserted in the slit or slot 19 in the side portion 15, the parts now appearing as indicated in Fig. 9, in which they are seen in assembled position and ready for delivery. The member 11 may sometimes be omitted. 55 If the device is to be mailed, instead of employing a flap 17, provided with a tab 18, the portion 16 of the device is provided with side flaps 24 and 25, which after the parts are folded are bent over the portion 15, and owing 60 to the provision of the interlocking portions 26 and 27 these are held in place. Instead, however, of employing a flap 17, provided with a tab 18, I employ a top flap 28, which is provided with a suitable adhesive material, as indicated at 29, so that after 65

this flap is bent over it may be suitably secured to the flaps 24 and 25, as will be readily apparent to those skilled in this art, the parts appearing as seen in Fig. 11, and the device is now ready for mailing.

It will be apparent to those skilled in this art that the different slips may be simultaneously written and readily detached when desired and that there is a great saving in both time and labor when a device embodying my invention is employed. The device may be cheaply manufactured, and the different slips may be printed or impressed with any desired data or advertising matter.

It will now be apparent that I have produced a novel and useful combination bill-head, duplicate, label, receipt, and envelop which embodies the features of advantage enumerated as desirable in the statement of invention and the above description, and 80 while I have preferred to show those embodiments thereof which I have found in practice to give satisfactory and reliable results it is to be understood that my invention is susceptible to modifications in various particulars without departing from the spirit and scope thereof or sacrificing any of its advantages.

Having thus described my invention, what I claim as new, and desire to secure by Let- 95 ters Patent, is—

1. A device of the character described, comprising in a single sheet an envelop, a bill-head attached thereto, a duplicate slip adjacent to and disconnected from the bill-head, and a label connected to the envelop and foldable in relation to said duplicate.

2. A device of the character described, comprising in a single sheet an envelop, a bill-head attached thereto, a duplicate slip adjacent to and disconnected from the bill-head, a label connected to the envelop and foldable in relation to said duplicate, and a receipt-slip adjacent the duplicate slip.

3. A device of the character described, comprising in a single sheet an envelop, a bill-head attached thereto, a duplicate slip adjacent to and disconnected from the bill-head, and a label connected to the envelop and foldable in relation to said duplicate, said envelop being provided with a panel through which the address on the bill-head is visible when the device is folded.

4. A device of the character described, comprising in a single sheet an envelop, a bill-head attached thereto, a duplicate slip adjacent to and disconnected from the bill-head, a label connected to the envelop and foldable in relation to said duplicate, and a receipt-slip adjacent the duplicate slip, said envelop being provided with a panel through which the address on the bill-head is visible when the device is folded.

5. A device of the character described, comprising in a single sheet an envelop, a

bill-head attached thereto, a duplicate slip adjacent to and disconnected from the bill-head, a label connected to the envelop and foldable in relation to said duplicate, and a receipt-slip adjacent the duplicate slip, said label and receipt being of less width than the bill-head.

6. A device of the character described, comprising in a single sheet an envelop, a bill-head attached thereto, a duplicate slip adjacent to and disconnected from the bill-head, a label connected to the envelop and foldable in relation to said duplicate, a receipt-slip adjacent the duplicate slip, said label and receipt being of less width than the bill-head, and an address portion foldably united to the end of the bill-head.

7. A device of the character described, comprising in a single sheet, an envelop and a bill-head attached thereto at the bottom thereof and of less length than the width of the two sides of the envelop, said envelop being provided with a panel through which the address on the bill-head is visible when the device is folded.

25 8. A device of the character described,

comprising in a single sheet, an envelop, a bill-head attached thereto, said envelop being provided with a panel through which the address of the bill-head is visible when the device is folded, and a label separate from said bill-head attached to said envelop.

9. A device of the character described, comprising in a single sheet, an envelop, a bill-head attached thereto, said envelop being provided with a panel through which the address on the bill-head is visible when the device is folded, and a receipt-slip separate from said bill-head attached to said envelop.

10. A device of the character described, comprising in a single sheet, an envelop, a bill-head secured thereto, and a duplicate slip separate from said bill-head secured to said envelop adjacent said bill-head, said envelop being provided with a panel through which the address on the bill-head is visible when the device is closed.
